Primary Examiner — Keli L Hill*(74) Attorney, Agent, or Firm* — Michael Best and Friedrich LLP(57) **CLAIM**

The ornamental design for an audio player, as shown and described.

DESCRIPTION

FIG. 1 is a front, bottom, right perspective view of an audio player showing my new design;

FIG. 2 is a front elevational view thereof;

FIG. 3 is a rear elevational view thereof;

FIG. 4 is a left side elevational view thereof;

FIG. 5 is a right side elevational view thereof; and,

FIG. 6 is a bottom plan view thereof.

The dot-dash broken lines represent the bounds of the claimed design, while all other broken lines are included for the purpose of illustrating portions of the audio player; the broken lines form no part of the claimed design.

1 Claim, 6 Drawing Sheets---
